ATTORNEY

UNITED STATES PATENT OFFICE.

JOHN A. WILLIAMS, OF RICHMOND HILL, NEW YORK.

CUFF BUTTON.

Application filed September 8, 1925. Serial No. 54,893.

The purpose of my invention is to provide a folding cuff-button which can be very easily inserted in, and removed from, the buttonholes of a cuff, and which shall be 5 very strong and hold reliably, which shall achieve excellence of appearance, which is essential in an article of this character, and which, while adapted to be made in either expensive or inexpensive forms, shall be inherently susceptible of economical manufacturing methods, and can be made to compete with moderate or low-priced forms of cuff-buttons and cuff-links now on the market, possessing less advantage. With these ends 15 in view, the invention may be said to comprise the novel matters of construction, combination and relation, in the novel device or article of manufacture, which will now be described with reference to two embodiments, and which will be more particularly pointed out in the claims.

In the accompanying drawings, forming part thereof:

Fig. 1 is a side elevation of the cuff-button in its closed position.

Fig. 2 is a similar view with the parts in the position they would assume when the cuff-button is being inserted into the cuff.

Fig. 3 is an end view with the parts in the same position as Figure 2.

Fig. 4 is a top plan view with the parts in the same position as Figure 1.

Fig. 5 is a longitudinal sectional view, the lower part being in elevation, and the cuff-button in its closed position.

Fig. 6 is a view similar to Figure 5, with the cuff-button partly opened.

Fig. 7 is a cross sectional view on the line 7-7 of Figure 1; and

Fig. 8 is a view partly in elevation and partly in section of a modified form.

The cuff-button has a base part 2, the shape of which may be varied. Rigid with the middle of the base part is a post 3. This post might be in one piece with the part 2, as far as the invention is concerned, and is preferably made hollow, in a suitable manner, to present a rectangular or oblong cross-section. The part 2 will be termed for convenience a base, and the mechanical part 4, to be described, a head; but it will be understood that the "base" may be given an ornamental treatment so as to constitute it the front of the cuff-button in point of appear-

ance, while the part 4 may be in appearance 55 the ornamental head, or it may be merely a retaining cross-bar suitable to be placed at the inner side of cuff; or again both parts may receive ornamental treatment or be so finished that it will be a matter of choice 60 with the user how the article is worn in the cuff. It is most advantageous for manufacture, and also desirable for appearance, that the part 4 have the shape of a bar, but I do not necessarily limit myself in this respect. 65

The part 4 comprises a pair of primary members or arms 5, the inner ends of which are pivoted to the upper portion of the post 3, on pins 6; and a pair of locking thrust 70 members 7, which are pivoted to the outer portions of the arms 5, on pins 8. In the condition of service shown in Figs. 1, 4 and 5, the members 5 and 7 lie together so that an apparently and virtually solid, or single 75 cross arm or cross head structure is formed. This is important both for appearance and for strength. This construction is best secured by arranging the members 5 and 7 to fit lengthwise on within the other, and especially by the utilization of a U section in one or both of the members.

Thus, the arms 5 comprise, each, two sides or flanges 9 and a bottom or connecting bridge 10, the whole being adapted to be cut 85 and formed economically from sheet metal. The bottom bridge 10 is cut away from both ends of each arm, or, stated otherwise, the side flanges 9 are extended at both ends beyond the bottom, forming two pairs of horns 90 11 and 13. The horns 11 at the inner ends of the arms embrace the post, and the pivot pins 6 pass through them and through the post. The inner ends 12 of the bridges 10 constitute stops which prevent the arms 95 from sagging below the transverse position.

The members 7 lie substantially within and preferably flush with, the members 5, and are preferably, though not necessarily likewise of channel section, having continuous tops, and edge flanges 14 on the under side, which receive the pivots 8, and desirably taper toward the locking ends 15.

In this embodiment the upper portion 16 of the post is interposed as an abutment or abutments between the free ends 15 of the members 7. Thus, the lateral corners of the post are notched in a suitable manner, as

indicated at 17, to form abutment seats for the said ends, against which the thrust members will bear endwise to lock the structure by greatly multiplied pressure against any 5 force acting away from the base 2, the locking being the stronger the greater the force tending to collapse the structure. The points of abutment engagement between the members 7 and the post preferably lie approximately in or near the line of center drawn 10 through the pivots 8. These points may also lie outwardly, or to the rear, of the pivots 6.

At their opposite ends, the locking members 7 are extended beyond their pivots 8, and beyond the outer ends of the arms 5 in the service position, so as to form unlocking ears 18. Pressure of the finger and thumb on these extensions toward the base 2 releases the lock, so that the members 5 and 7 can be straightened out substantially in line with the post 3, as seen in Figs. 2 and 3. The relations are such that the two halves of the mechanism, when straightened out or extended in this manner, match together to form a sort of needle or spike, which threads easily through the holes of the cuff. The recesses between the outer horns 13 of the arms 5 accommodate the unlocking ears 18 of the member 7 when the parts are swung from the service position to the threading position, and vice-versa.

The several relatively movable parts are fitted together tightly so as to provide fairly 35 stiff frictional resistance to change of position. In case of wear, this frictional stiffness can be easily restored by pinching.

Such friction will in itself prevent any 40 accidental opening of the lock. For further security, however, the top or face of each of the abutment seats 17 is slightly undercut, or overhung, as indicated, so as to oppose disengagement. The effect is best obtained when the length of the members 7 between their pivots 8 and their ends 15 is 45 slightly longer than the distance to the maximum overhang of the abutment, so that the members 7 must be forced into and out of locking positions with something of a snap action.

The construction shown in Fig. 8, bears a 50 general resemblance to the preferred device which has been described. A base is marked 2^a, a post 3^a, arms 5^a, thrust members 7^a, the pivots 6^a and 8^a. The chief difference is that the ends 15^a of the members 7^a abut 55 against each other on top of the post, instead of abutting endwise against the post as in the other construction. In a form 60 of this kind, I do not necessarily limit myself to the ends 15^a being free ends, but free locking ends are highly advantageous for reasons of simplicity, compactness, neatness and general effectiveness. In this form 65 if one side of the cross head is unlocked,

both sides are unlocked; but in the preferred form, where free ends of the members 7 abut against fixed abutment on the post, either side will remain locked even though the other side should become unlocked. 70

The modified construction is unlocked by pressing on the extensions 18^a of the members 5^a, and the two halves of the cross head may then be straightened out and brought together in line with the post, for insertion 75 in, or removal from, the cuff, as in the other form. When the parts are in the service position, they nest or interfit in the manner which has been described, so as to make a strong and practically unitary cross arm. 80

The designs of both forms is such that they can be made of sheet metal, which is a substantial advantage for economical manufacture and likewise for appearance. 85

Still other forms, changes and embodiments are within the scope of the invention.

One of the advantages of the invention results from the fact the plan permits of the post being quite short, causing the cuff-button to hold the sides of the cuff closely giving a nice effect. When the button is unlocked by depressing the ears 18 or 18^a, the ears will not rub the fabric so as to cause wear, because the arms 5 or 5^a will simultaneously swing upward so as to carry the ears away from the cuff. The members 7 and 7^a add length to the device when in the threading position, so as to facilitate insertion of the cuff-button. 95

What I claim as new is:

1. A cuff-button, comprising a base part, a fixed post, a pair of arm members pivoted to said post, and a pair of locking thrust members pivoted to the outer portions of said arm members, the arm members and thrust members adapted to be extended endwise from the post or to be folded together laterally, each arm member and its thrust member lying together in the latter condition so as to form a virtually solid cross head on the post. 100

2. A cuff-button, comprising a base part, a fixed post, a pair of arm members pivoted to said post, and a pair of locking thrust members pivoted to the outer portions of said arm members, the arm members and thrust members adapted to be extended endwise from the post or to be folded together laterally, the arm members and thrust members being adapted to be received and lie one within the other in the latter condition so that a virtually solid cross head is formed. 110

3. A cuff-button, comprising a base part, a fixed post, a pair of arm members pivoted to said post, and a pair of locking thrust members pivoted to the outer portions of said arm members, the arm members and thrust members adapted to be extended endwise from the post or to be folded together laterally, the members having a 120

substantially **U** section so arranged that the members fit and lie one within the other in the folded or adjusted condition.

4. A cuff-button, comprising a base part, 5 a fixed post, a pair of arm members pivoted to said post, and a pair of locking thrust members pivoted to the outer portions of said arm members, the arm members and thrust members adapted to be extended endwise from the post or to be folded together laterally, the arm members having a substantially **U** section in which the thrust members lie in the folded or adjusted condition.

5. A cuff-button, comprising a base part, 15 a fixed post, a pair of arm members pivoted to said post, and a pair of locking thrust members pivoted to the outer portions of said arm members, the arm members and thrust members adapted to be extended endwise from the post or to be folded together laterally, the arm members having a substantially **U** section between the sides of which the thrust members fit, the said sides extending at the inner end beyond 25 the bottom of the section to embrace a portion of the post to which they are pivoted.

6. A cuff-button, comprising a base part, a fixed post, a pair of arm members pivoted to said post, and a pair of locking thrust members pivoted to the outer portions of said arm members, the arm members and thrust members adapted to be extended endwise from the post or to be folded together laterally, the arm members having a substantially **U** section between the sides of which the thrust members fit, the said sides extending at the inner end beyond 35 the bottom of the section to embrace a portion of the post to which they are pivoted, the inner end of the bottom of each arm constituting a stop abutting the post in the adjusted position.

7. A cuff-button, comprising a base part, a fixed post, a pair of arm members pivoted to said post, and a pair of locking thrust members pivoted to the outer portions of said arm members, the arm members and thrust members adapted to be extended endwise from the post or to be folded together laterally, the arm members having a substantially **U** section in their intermediate portions, the said sides extending at both ends beyond the bottom bridge of the section, the inner ends of the sides having 50 the thrust members pivoted between them, the said thrust members being extended beyond their pivots to form unlocking ears which project at the outer ends of the arms in the adjusted position.

8. A cuff-button, comprising a base part, 60 a fixed post, a pair of arm members pivoted to said post, a pair of locking thrust members pivoted to the outer portions of said arm members, the arm members and thrust members adapted to be extended endwise

from the post or to be folded together laterally, and unlocking means comprising portions of said thrust members beyond their pivots projecting in the folded or adjusted position.

70

9. A cuff-button, comprising a base part, a fixed post, a pair of arm members pivoted to said post, and a pair of locking thrust members pivoted to the outer portions of said arm members, the arm members and thrust members adapted to be extended endwise from the post or to be folded together laterally, said thrust members having free locking ends.

75

10. A cuff-button, comprising a base part, 80 a fixed post, a pair of arm members pivoted to said post, and a pair of locking thrust members pivoted to the outer portions of said arm members, the arm members and thrust members adapted to be extended endwise from the post or to be folded together laterally, said thrust members having free ends which abut against the post.

85

11. A cuff-button, comprising a base part, 90 a fixed post, a pair of arm members pivoted to said post, and a pair of locking thrust members pivoted to the outer portions of said arm members, the arm members and thrust members adapted to be extended endwise from the post or to be folded together laterally, said thrust members having free ends, and said fixed post having an interposed abutment.

95

12. A cuff-button, comprising a base part, 100 a fixed post, a pair of arm members pivoted to said post, and a pair of locking thrust members pivoted to the outer portions of said arm members, the arm members and thrust members adapted to be extended endwise from the post or to be folded together laterally, said thrust members having free ends, and said fixed post having notched 105 abutment seats for said members.

100

13. A cuff-button, comprising a base part, 110 a fixed post, a pair of arm members pivoted to said post, and a pair of locking thrust members pivoted to the outer portions of said arm members, the arm members and thrust members adapted to be extended endwise from the post or to be folded together laterally, said thrust members having free ends, and said fixed post affording abutment for said members, together with means for snap engagement between said members and post.

115

14. A cuff-button, comprising a base part, 120 a fixed post, a pair of arm members pivoted to said post, and a pair of locking thrust members pivoted to the outer portions of said arm members, the arm members and thrust members adapted to be extended endwise from the post or to be folded together laterally, said thrust members having free ends, and said fixed post having an interposed undercut abutment.

125

130

15. A cuff-button, comprising a base part, a fixed post, a pair of arm members pivoted to said post, and a pair of locking thrust members pivoted to the outer portions of said arms and having free locking ends, the arm members and thrust members adapted to be extended endwise from the post or to be folded together laterally, each arm member and its thrust member lying together in the latter condition so as to form a virtually solid cross head on the post.

16. A cuff-button, comprising a base part, a fixed post, a pair of arm members pivoted to said post, a pair of locking thrust members pivoted to the outer portions of said arms and having free locking ends, abutments on the fixed post for said ends, the arm members and thrust members adapted to be extended endwise from the post or to be

folded together laterally, each arm member and its thrust member lying together in the latter condition so as to form a virtually solid cross head on the post.

17. A cuff-button, comprising a base part, a fixed post, a pair of arm members pivoted to said post, a pair of locking thrust members pivoted to the outer portions of said arms and having free locking ends, abutments on the fixed post for said ends, the arm members and thrust members adapted to be extended endwise from the post or to be folded together laterally with said thrust members in engagement with said abutments, the points of thrust lock between said members and abutments lying somewhat above and outwardly of the main pivots of the arms.

JOHN A. WILLIAMS.
